ROD CLIP

Robert M. Albert, Chicago, Ill.

Application March 1, 1946, Serial No. 651,067

3 Claims. (Cl. 24—81)

1

The invention relates to improvements in garment blockers and more particularly to a structure embodying novel means for enabling adjustment of a garment blocker to accommodate garments of various sizes, and for securing it in such adjusted position.

Garments are normally of varied size and style to conform with the dimensional and shape characteristics of different individuals. When garments of knit construction are laundered, it is common practice to employ suitable means for retaining the garment in substantially its initial dry configuration, while in some instances it is desirable to stretch various portions thereof to overcome certain deficiencies in the original size and shape of the garment. Stretching and blocking of a garment of knit construction is best accomplished by fitting the garment on a suitable frame embodying the desired size and shape characteristics. However, such frames, which are commonly referred to as garment blockers, necessarily are adjustable in their construction so as to accommodate garments of various sizes, and to adapt the blocker for use as a stretcher.

Various devices have been proposed for affording means to facilitate ready adjustment of garment blockers of the kind referred to. Many such means, however, embody structures which interfere with the garment when the latter is arranged on the blocker, while other structures are difficult to manipulate, or otherwise embody such characteristics as not to make them entirely satisfactory.

It is, therefore, an object of the present invention to provide a garment blocker with novel means to facilitate adjustment and subsequent securing of the blocker after adjustment to accommodate garments of various sizes and shapes.

Another object is to provide a novelly constructed clamp for cooperating with relatively movable portions of a garment blocker to retain said blocker in various positions of adjustment.

Another object is to provide an improved, simple and dependable means for maintaining a garment blocker in adjusted position and for effecting ready release of the parts held thereby.

Other and further objects of the present invention will be apparent from the following description and claims and are illustrated in the accompanying drawing which, by way of illustration, shows a preferred embodiment and the principle thereof and which is considered to be the best mode contemplated for applying that principle. Other embodiments of the invention

5 embodying the same or equivalent principle may be used and structural changes may be made as desired by those skilled in the art without departing from the present invention and a purview of the appended claims.

In the drawing:

Fig. 1 is a front elevational view of a garment blocker embodying features of the present invention, and showing a portion of one of the arm frames thereof broken away.

Fig. 2 is an enlarged elevational view of one of the clamps employed to frictionally bind the relatively adjustable parts of the garment blocker associated therewith against relative movement.

Fig. 3 is a side elevational view of the clamp, as shown in Fig. 2.

Fig. 4 is a sectional view taken on line 4—4 of Fig. 2.

20 In the exemplary embodiment of a garment blocker shown in the accompanying drawing, said blocker includes a body portion consisting of a pair of frame members 11 and 12 which are adapted to cooperate with each other to define a substantially rectangular frame of such size and shape as to be readily received within a garment. Each of the members 11 and 12 is fashioned from suitable stiff wire or rod stock, and the member 11 has end extensions 13 and 14 which project in the direction of the member 12 to overlie similar extensions 15 and 16 on said member 12. The related extensions 13—15 and 14—16 are adapted to be moved longitudinally relative to each other in such manner that the overall width of the blocker frame may be varied to suit variously sized garments. In use, the blocker frame is inserted into the body of the wet garment, and the frame members 11 and 12 are moved away from one another so as to draw the garment substantially taut.

40 Suitable means, such as hook elements 17, are provided on the ends of one of each pair of the co-related end extensions 13—15 and 14—16 so as to guide them in their related movement. A clamp, generally indicated at 18, also is associated with the related pairs of end extensions 13—15 and 14—16, which clamp embodies means adapted to be actuated for frictionally binding the related extensions one to the other so as to prevent relative movement therebetween. These clamps 18 are of such construction as to lie within the plane of the frame so as not to interfere with the garment arranged thereover.

45 As best shown in Figs. 2, 3 and 4, the clamp 18 consists of a strap of relatively stiff sheet stock bent substantially U-shaped and fitted over

one of the extensions, such as 16, with its projecting leg portions 19 embracing the other of the extensions, such as 14. The leg portions 19 of the clamp are of a length to extend a considerable distance beyond the extension 14, as shown, so as to afford means for pivotally connecting a U-shaped lever 21 thereto. The bifurcated lever 21 embraces the leg portions 19 and is pivotally secured thereto as by means of a pin or rivet 22 which extends through both the walls of the lever 21 and leg portions 19. The pin 22 is formed with heads 25 substantially larger in diameter than the diameter of the pin body so as to thereby provide positive means to prevent spreading of the U-shaped lever 21.

The corner portions 23 of the leg portions 19 of the clamp 18 are each flared outwardly into the plane of the U-shape lever 21 so that when the lever 21 is moved about its pivot 22 from the full line position shown in Fig. 2 into either one of the dotted line positions illustrated, the flared corners 23 are engaged by said lever and act as cams to urge the leg portions 19 of the clamp inwardly towards each other to frictionally bind the rod extensions 14-16 therebetween. Such frictional binding of the rod extensions 14-16 prevents relative movement of said frame members 11 and 12 and thereby retains the blocker frame in a position of adjustment. Suitable protuberances 24 are formed in each of the leg portions 19 of the clamp to provide positive stops for limiting pivotal movement of the lever 21 so that said lever cannot, at any time, be moved over and beyond the flared corners 23.

It should be quite evident that the clamp 18 embodies manually actuatable means for effecting release or clamping of the related frame extensions associated therewith, and that said means is confined wholly within the plane of the blocker frame so that at no time will it interfere with a garment arranged thereover. The clamp further is of such construction as to be easily operated by inexperienced persons and is very positive in operation. The garment blocker illustrated is, of course, provided with suitable arm extensions 26 which may be suitably attached as by clips 27 to the respective frame portions 11 and 12.

Although an exemplary form of the invention has been disclosed herein, it should be understood that it is capable of embodying a wide variety

of modifications in detail construction and that a greater number of clamps 18 than is shown may be provided to increase the adjustability of the frame blocker, without departing from the spirit of the invention or the scope of the appended claims.

I claim:

1. A clamp for binding two rods laid side by side against relative sliding movement comprising a strip of shape-retaining material formed substantially U-shape with its leg portions embracing said rods, a bifurcated lever pivotally connected to both leg portions, and cam surfaces on said leg portions engageable by said lever to compress the clamp tightly about said rods to prevent relative movement of said rods.

2. A clamp for binding two rods laid side by side against relative sliding movement comprising a strip of shape-retaining material formed substantially U-shape with its leg portions embracing said rods, cam surfaces on the ends of said leg portions, and a bifurcated lever pivotally connected to both leg portions, said lever being selectively movable into engagement with said cam surfaces to compress the clamp portions tightly about the rods.

3. A clamp for binding two rods laid side by side against relative sliding movement comprising a strip of shape-retaining material formed substantially U-shape with its leg portions embracing said rods, cam surfaces on the ends of said leg portions, a bifurcated lever pivotally connected to both leg portions, said lever being selectively movable into engagement with said cam surfaces to compress the clamp portions tightly about the rods, and stops on said leg portions to limit pivotal movement of said lever.

ROBERT M. ALBERT.
